[57] CLAIM

The ornamental design for Christmas tree collectable display stand, as shown and described.

DESCRIPTION

FIG. 1 is a perspective view of Christmas tree collectable display stand showing the new design, the back view being a mirror image.

FIG. 2 is a right side view of the Christmas tree collectable display stand shown in FIG. 1, the opposite side view being a mirror image.

FIG. 3 is a view from the top of the Christmas tree collectable display stand shown in the prior Figures.

FIG. 4 is a view of the bottom of the Christmas tree collectable display stand shown in prior Figures; and,

FIG. 5 is an enlarged fragmentary view of encircled area 5 in FIG. 2, shown separately for clarity of the needles of the design.

The Christmas tree collectable display stand is a display for holding collectable items.

The drawing is lined for color.
